UNITED STATES PATENT OFFICE

2,689,038

TYPOGRAPHICAL COMPOSING MACHINE

John H. Hilpman, Springfield Gardens, N. Y., assignor to Mergenthaler Linotype Company, a corporation of New York

Original application September 7, 1950, Serial No. 183,620, now Patent No. 2,667,265, dated January 26, 1954. Divided and this application February 7, 1952, Serial No. 270,471

4 Claims. (Cl. 199—19)

1

This invention relates to typographical composing machines such as "Linotype" machines of the general organization represented in Letters Patent of the United States to O. Mergenthaler, No. 436,532, wherein circulating matrices are released from a magazine in the order in which their characters are to appear in print, the composed line transferred to the face of a mold, the mold filled with molten metal to form a slug or "linotype" against the matrices which produce the type characters thereon, and the matrices thereafter returned through distributing mechanism to the magazine from which they started.

More particularly, it relates to that class of mixing machines designed to handle matrix fonts which differ from one another in the size and number of characters, for example, the regular ninety character text fonts used exclusively for the composition of straight matter, and the special seventy-two character fonts used for the composition of head letter or display matter.

The matrix storage magazines employed in machines of this class are of standard size and shape (although certain features of the present invention are particularly applicable to magazines of the wide variety), but differ in the number and arrangement of their matrix channels, the regular magazines being provided with ninety-one channels spaced apart in the usual way to accommodate the matrix columns of the text fonts, while the display magazines are provided with but seventy-three channels spaced apart in a different way to accommodate the matrix columns of the larger special fonts. The magazines are arranged in superposed pairs, each pair comprising a ninety character magazine and a seventy-two character magazine, and the matrices stored therein can be selectively released from either by the operation of the same keyboard and without the necessity of raising or lowering the magazines. Moreover, after the casting operation has been completed the matrices are automatically returned and redistributed into the proper channels of the magazine from which they were released.

In view of the fact that a single keyboard is employed to effect the release of the matrices from two separate magazines having different numbers and spacings of matrix escapement devices, it has been customary to provide separate groups of connecting devices in the form of long reeds as the means for mechanically connecting the keyboard to the magazine escapements, one group of said reeds serving to operate the ninety character magazine escapements and the other group serving to operate the seventy-two character

magazine escapements. In addition, a movable throat section is generally provided, capable of adjustment so as to conduct matrices from either adjacent magazine into a channeled raceway or front plate common to both magazines. Various shifting mechanisms for adjusting the throat section into registry with the selected magazine and for automatically connecting the appropriate group of reeds have been heretofore disclosed, one of the more recent disclosures being described in U. S. patent to Frolander No. 2,399,999, but the shifting mechanism herein shown and described is of the kind disclosed in co-pending application Serial No. 183,620, filed September 7, 1950, now U. S. Patent No. 2,667,265, wherein the two groups of long connecting reeds are mounted in a frame which is hinged at the top, permitting the lower ends of either group to be selectively brought into operative alignment with the keyboard elements.

20 The present invention is directed to a new and improved arrangement of the connecting reeds to enable a standard width keyboard to be used in association with magazines of much greater than standard width.

25 Referring to the drawings:

Fig. 1 is a side elevation, partly in section, of a portion of a Linotype machine equipped with the present improvements;

Fig. 2 is a view similar to that shown in Fig. 1 with the parts in a different shifted position;

Fig. 3 is a horizontal section taken on the line 3—3 of Fig. 2;

Fig. 4 is a front elevation showing the arrangement of the long connecting reeds and the shiftable frame thereof;

Fig. 5 is an enlarged perspective view showing the arrangement of the long connecting reeds in greater detail; and

Fig. 6 is a fragmentary front elevation, showing the operation of one of the connecting reeds.

As shown in Fig. 1, the machine is equipped with four superposed magazines, A¹, A², A³ and A⁴, capable of being raised and lowered in the machine frame by operation of a crank handle B in order to bring either the upper or lower pair of magazines into operative relation with the assembler entrance C and the distributing mechanism (not shown). The second and fourth magazines A² and A⁴ are of the regular or standard form and adapted to contain the ordinary ninety character text fonts, whereas the first and third magazines A¹ and A³ are of a different form and adapted to contain the special seventy-two character display fonts.

The assembler entrance C includes an upper

throat section C¹ to cooperate with the magazine A¹ or A³; a lower partitioned bridge member C³ to cooperate with the magazine A² or A⁴; and an adjustable throat section C² to cooperate with either the throat section C¹ or the bridge member C³. The throat section C is hingedly mounted in the front side brackets O of the machine frame and may be swung forwardly when desired for access to the magazines; and the adjustable throat section C² is fastened to a horizontal rock shaft C⁴ likewise journaled in the front side brackets O and provided with a crank arm C⁵ operable to swing the throat section forwardly and backwardly in effecting its adjustments. An overhead banking screw U¹ (see Fig. 2), secured to the side plate O¹ of the machine frame and arranged to engage the upper edge of the crank arm C⁵, locates the throat section C² in its forwardly adjusted position, i. e. in registry with the lower end of the throat section C¹, while a similar screw (not shown), also secured to the side plate O¹ and arranged to engage the under edge of the crank arm C⁵, locates the throat section C² in its rearwardly adjusted position, i. e. in registry with the bridge member C³. In either of its adjusted positions, the throat section C² is adapted to conduct the matrices released from the selected magazine into a fixed vertically disposed channelled raceway C⁷ from which the matrices are directed to the assembler proper for composition in line.

Each of the several magazines is provided with matrix releasing escapements a; and the actuating devices therefore include, generally, a series of fore-and-aft pivoted levers D, a corresponding series of actuating slides D¹ carried by the throat section C², and a series of small actuating elements D² mounted in the throat section C¹ and operable by the slides D¹. The levers D are controlled from a keyboard E through the medium of two sets of vertical reeds D³, D⁴, which will be described in detail below.

The adjustment of the throat section C² into either of its alternate positions is made by a hand lever F which, as shown in Fig. 3, is attached to one end of a short shaft F¹ mounted in the front bracket O² of the machine frame. At the opposite end of the shaft F¹, a small rocker arm F² is attached and connected to a bell crank F³ by means of a link F⁴. The bell crank F³ is fast to a short rock shaft F⁵ and the horizontally disposed arm thereof is pivotally connected to a long rod F⁶ which extends vertically upward and is loosely connected to the crank arm C⁵ by means of a pivot pin F⁷ projecting into an elongated slot formed in the arm. The pin F⁷ is carried by a lever F⁸ which is pivotally mounted on the shaft C⁴ for the crank arm C⁵.

Conventional locking mechanism G, such as disclosed in the Frolander Patent No. 2,399,999, is employed for locking the throat section C² in its different adjusted positions and for releasing it preparatory to its adjustments.

As explained hereinabove, separate sets of vertical reeds D³, D⁴ are provided for actuating the fore-and-aft levers D, the reeds D³ being the operative set to release the matrices from the upper operative magazine A¹, when the throat section C² is in its forward position in registry with the lower end of the throat section C¹ (Fig. 2), and the reeds D⁴ being the operative set to release the matrices from the lower operative magazine A², when the throat section C² is in its rearward position in registry with the bridge member C³ (Fig. 1). Both sets of reeds D³, D⁴ are slidably supported in an adjustable frame J through slots

in the lower L-shaped plates J¹, J² and the upper flat plates J³, J⁴. Also the reeds situated at the left hand side of the machine are given additional support and guidance by the slotted brace R (Fig. 4).

The reed frame J is hinged at the top in end supports J⁵, attached to the side plates O¹ of the machine frame, in such a way that the entire frame can be swung to bring the lower ends of either set of reeds D³, D⁴ into alignment with a single set of actuators E¹ operated from the keyboard E while maintaining the upper ends of the reeds of both sets in engaging relation to the overlying levers D. Both sets of reeds D³, D⁴ are provided at their lower ends with shoulders adapted to bank on a supporting bar J⁶ carried by the reed frame (see Figs. 4 to 6).

The shifting of the reed frame J, like the shifting of the throat section C², is accomplished under the control of the hand lever F. A lever J⁷ is fixed to the short rock shaft F⁵, and a lever J⁹ is likewise fixed to a second long rock shaft J⁸, the latter extending across the entire width of the reed frame (Fig. 3). The levers J⁷ and J⁹ are pivotally connected by a link J¹⁰, and hence the shaft J⁸ may be rocked in either direction under the control of the hand lever F. Also fixed to the shaft J⁸ are two further levers J¹¹, pivotally connected by links J¹² to the lower end of the reed frame J near its opposite edges. It is, therefore, clear that when the hand lever F is raised to bring the throat section C² into registry with the throat section C¹, the reed frame J will at the same time be pivoted in its supporting bearings J⁵ to bring the set of reeds D³ into operative alignment with the keyboard actuators E¹ (Fig. 2). Likewise, when the hand lever F is depressed to adjust the throat section C² into registry with the bridge member C³, the reed frame will again be pivoted in its supporting bearings to bring the set of reeds D⁴ into operative association with the key controlled actuators E¹ (Fig. 1).

In order to lighten the burden of operating the hand lever F and, particularly, to counterbalance the weight of the adjustable throat section C², a weight C⁹ is pivotally suspended from the bracket O³ by means of the lever C¹¹, which is pivotally connected to the lowermost extremity of the crank arm C⁵ by a connecting link C¹⁰. The lever C¹¹ is provided with a screw extension C¹² to which the weight C⁹ is threadably connected, so that the counterbalancing force can be varied to meet different conditions.

Coming now to the present invention: When magazines of the wide variety are employed, the width of the lower discharge end thereof is much greater than the width of the keyboard E, generally protruding to the right of and beyond said keyboard. As shown in Fig. 4, many of the reeds D³, D⁴ at the right hand side of the machine are bent laterally to the right in order to actuate the escapements a located beyond and to the right of the cam controlled actuators E¹. These reeds are made somewhat thicker and stronger than ordinarily so that they will not be unduly weakened by the degree of bending required. Also, as best shown in Fig. 5, the bent or diagonal portion of every other reed D³' of the group D³ is offset in a forward edgewise direction so that its rear edge d will stand clear of the forward edge d¹ of the adjacent reed to the right. Likewise, the bent or diagonal portion of every other reed D⁴' of the group D⁴ is offset in a rearward edgewise direction so that its forward edge d² will stand clear of the rear edge d³ of the adjacent reed to the

right. The vertical end portions of all reeds of either group are, however, in transverse alignment and parallel, as usual, to cooperate with the keyboard actuators E¹ at their lower ends and with the escapement levers D at their upper ends. As the reeds are thus constructed, and as illustrated in Fig. 6, when a non-offset reed D³ or D⁴ is raised to release a matrix, its bent or diagonal portion will be free to move past the bent or diagonal portion of the adjacent offset reed to the left and thus avoid any interference between adjacent reeds notwithstanding their close spacing.

This application is a true division of parent application Serial No. 183,620, filed September 7, 1950, now U. S. Patent No. 2,667,265.

What is claimed is:

1. In or for a typographical composing machine, escapement actuating mechanism comprising a series of vertically movable reeds arranged side by side in closely spaced relation, each reed presenting two vertical end portions disposed in laterally displaced vertical planes, and an intermediate diagonal portion connecting the two vertical end portions, the diagonal portions of said reeds being inclined in the same direction and arranged in substantially parallel relation, the diagonal portions of alternate reeds being offset in an edgewise direction with reference to the diagonal portions of the intermediate reeds, with the rear edge of the diagonal portion of one reed positioned forwardly of the forward edges of the diagonal portions of the next two adjacent reeds, whereby to prevent interference between adjacent reeds in their vertical movements.

2. In or for a typographical composing machine, escapement actuating mechanism comprising a series of vertically movable reeds arranged side by side in closely spaced relation, each reed presenting two vertical end portions disposed in lateral displaced vertical planes, and an intermediate diagonal portion connecting the two vertical end portions, the diagonal portions of said reeds being inclined in the same direction and arranged in substantially parallel relation, the diagonal portions of alternate reeds being offset forwardly in an edgewise direction with reference to the diagonal portions of the intermediate reeds, with the rear edge of the forwardly offset diagonal portion of one reed positioned forwardly of the forward edges of the diagonal portions of the next two adjacent reeds, whereby to prevent interference between adjacent reeds in their vertical movements.

3. In or for a typographical composing ma-

chine, escapement actuating mechanism comprising a series of vertically movable reeds arranged side by side in closely spaced relation, each reed presenting two vertical end portions disposed in laterally displaced vertical planes, and an intermediate diagonal portion connecting the two vertical end portions, the diagonal portions of said reeds being inclined in the same direction and arranged in substantially parallel relation, the diagonal portions of alternate reeds being offset rearwardly in an edgewise direction with reference to the diagonal portions of the intermediate reeds, with the front edge of the rearwardly offset diagonal portion of one reed positioned rearwardly of the rear edges of the diagonal portions of the next two adjacent reeds, whereby to prevent interference between adjacent reeds in their vertical movements.

4. In or for a typographical composing machine, escapement actuating mechanism comprising two series of vertically movable reeds, one series being arranged behind the other, the reeds in each series being arranged in closely spaced relation and each reed in each series presenting two vertical end portions disposed in laterally displaced vertical planes, and an intermediate diagonal portion connecting the two vertical end portions, the diagonal portions of the reeds in both series being inclined in the same direction and arranged in substantially parallel relation in each series, the diagonal portions of alternate reeds in the front series being offset forwardly in an edgewise direction with reference to the diagonal portions of intermediate reeds, with the rear edge of the forwardly offset diagonal portion of one reed positioned forwardly of the forward edges of the diagonal portions of the next two adjacent reeds, and the diagonal portions of alternate reeds in the rear series being offset rearwardly in an edgewise direction with reference to the diagonal portions of the intermediate reeds, with the front edge of the rearwardly offset diagonal portion of one reed positioned rearwardly of the rear edges of the diagonal portions of the next two adjacent reeds, whereby to prevent interference between adjacent reeds in either series in their vertical movements.
